UNITED STATES PATENT OFFICE.

ALBERT HENRY MIDGLEY AND BENJAMIN REED, OF LONDON, ENGLAND.

CONTROLLING DEVICE FOR ELECTRIC MOTORS FOR DRIVING SEWING-MACHINES, SMALL LATHES, &c.

No. 850,947.

Specification of Letters Patent.

Patented April 23, 1907.

Application filed January 31, 1906. Serial No. 293,827.

To all whom it may concern:

Be it known that we, ALBERT HENRY MIDGLEY and BENJAMIN REED, subjects of the King of Great Britain and Ireland, and both residents of 128 Southwark street, London, England, have invented certain new and useful Improvements in Controlling Devices for Electric Motors for Driving Sewing-Machines, Small Lathes, and the Like Machinery, of which the following is a specification.

This invention relates to a controlling device for direct-current electric motors, and consists, essentially, in a new or improved controlling switch by means of which it is possible to at once run the requisite machine at full speed, slow speed, varying speed, or stopped altogether by the release or otherwise of a single lever, such controlling device being especially intended for sewing-machines electrically operated, but applicable also to other machines, such as small lathes and the like.

Referring to the accompanying sheet of explanatory drawings in carrying the said invention into effect, *a* represents a case or box of any suitable size and construction, and *b* the switchboard carried therein. On pivot *c* is mounted the (preferably spring-controlled) lever *d*, adapted to engage at its outer end with a sector *e* and with the stops or contacts *f* of the resistance *g*, arranged in any suitable manner within the case or box. This resistance *g* is connected, as shown, with the terminal *h*, and pivot *c* of the lever *d* with the terminal *i*. The sector *e* is connected to terminal *j*, and terminal *j* to the terminal *k*, and terminal *l* to terminal *m* to terminal *n*, which represents one end of the field-winding of the motor, the other end *o* of the winding being connected to the terminal *h*, terminals *p* and *q* of the commutator-brushes being connected to terminals *k* and *i*.

In connecting up the controlling-switch (indicated by *A*) as a whole with the motor *B* and supply mains, the terminals *m*, *h*, *i*, and *k* on the controlling-switch are connected up to the terminals *n*, *o*, *p*, and *q*, respectively, on the motor, and the terminals *j* and *l* to the mains *r* and *s*.

By the use of a controlling device constructed in accordance with this invention it is possible to start the motor, and consequently the machine, regulate the machine according to the amount of resistance put

in, or to stop the same instantaneously. For instance, when the contact-lever *d* is in the position shown in the accompanying drawings—*i. e.*, in engagement with the sector—the motor is at rest; but if said lever be moved in the direction of the arrow the motor will start the instant said lever *d* has left the sector *e* and stops or contacts *f**, connected to the resistance *g*, the speed of the motor increasing as the contact-lever *d* traverses over the stops *f* of said resistance. If now the lever *d* be moved in a direction opposite the arrow, the speed decreases until said lever makes contact with the sector *e* when the supply of current is cut off directly the lever has passed over the stops *f**. In order to obtain an instantaneous stop, the lever must make contact both with the sector *e* and one of the three contacts *f** opposite said sector. It will be observed that this action is secured by reason of the fact that when the lever *d* contacts with both the sector *e* and with one of the contacts *f** the motor-armature is short-circuited while the fields are kept excited, thereby providing a dynamic brake which immediately arrests the armature-shaft and stops the machinery driven thereby. The controlling device is made of such a shape and size as to be fitted in any convenient place—for instance, beneath the table of a sewing-machine—in which case the lever *d* is provided with a spring-controlled drum *t* and is operated by a cord *u* or the like connected to any suitable arrangement of pedal, or the lever *d* may be operated by a handle or in any suitable manner without departing from the nature of the invention.

What we claim as new, and desire to secure by Letters Patent of the United States, is—

In a controlling device for electric motors, the combination with the motor, of a switchboard having a plurality of resistance-contacts arranged on the arc of a circle, a resistance having connections with the individual resistance-contacts, a group of auxiliary contacts arranged on the arc of a circle beyond and connected with one of the terminals of said resistance-contacts, a field-wire connection from the motor-field to the resistance-contacts, a sector-contact included in the supply-circuit and having a connection with the motor-armature, said sector-contact being arranged concentric

2
to but spaced from said auxiliary contacts, and a suitably-operated contact-lever arranged to engage the sector-contact, and also said other contacts, the said contact-lever being adapted to simultaneously engage the sector-contact and an auxiliary contact.

In testimony whereof we have affixed our signatures in presence of two witnesses.

ALBERT HENRY MIDGLEY,
BENJAMIN REED.
